UNITED STATES PATENT OFFICE.

JOHN A. EVANS, OF TYRONE, PENNSYLVANIA, ASSIGNOR TO THE P & M COMPANY, OF CHICAGO, ILLINOIS, A CORPORATION OF ILLINOIS.

RAIL ANCHOR.

Application filed February 26, 1927. Serial No. 171,247.

This invention relates to rail anchors and has for its general object the provision of an improved rail anchor device adapted to engage opposite edges of the rail base and to maintain a strong grip thereon by spring pressure.

A specific object of the invention is to provide an improved rail anchor device having rail gripping portions so disposed with relation to a point of bearing of the device against the rail that the said end portions have a differential gripping action on the rail base, when the anchor device is driven transversely of the rail to its applied position.

Another object is to provide an anchor device of the above character in which the parts are so disposed with relation to each other and to the base of the rail that movement of the anchor transversely of the rail toward its applied position so distorts the anchor that the stress in the metal exerts a resilient pressure for maintaining the device in firm gripping engagement with the rail base. In this connection, the invention contemplates as one specific embodiment, a one-piece spring gripping anchor in which the stress in the metal exerts a pressure in a direction tending to force the anchor device transversely of the rail in a direction to maintain a firm grip on the rail base and to also hold the anchor in its normal gripping position on the rail against any tendency that the momentary pressures and other disturbing influences, incident to the passing of traffic, may have to loosen the grip of the device on the rail.

A further specific object of the invention is to provide an improved one piece spring anchor, in which the body and one end thereof are so flexed during its application to a rail, and the flexed end is so disposed with relation to the rail base that the tendency which the device has to return to the position from which it was sprung, exerts a pressure transversely of the rail to force a jaw portion at the opposite end of the anchor further upon the rail base and to also exert a spring pressure tending to rock the said jaw end of the anchor about an axis extending longitudinally of the rail to increase its grip on the rail base.

The invention contemplates such other objects as will appear from the detailed de-

scription of the specific embodiment of the invention shown in the accompanying drawing.

In the drawing:

Fig. 1 is a plan view of the railroad rail and a portion of a cross tie showing the rail anchor device, constructed in accordance with my invention, applied to the base flange of the rail, in position to bear against a vertical face of the cross tie.

Fig. 2 is a cross section through the rail base and showing the anchor device in a position assumed during its application to a rail.

Fig. 3 is a view similar to Fig. 2 showing in dotted lines the initial position of the anchor before the same is driven transversely of the rail base, and showing in full lines the applied position of the anchor, and

Fig. 4 is a view in perspective of the rail anchor device removed from the rail base.

The principles of the invention may be embodied in anchor devices of various forms and constructions. For convenience of illustration, I have shown in the drawings one form of rail anchor constructed in accordance with my invention. The rail anchor illus-

trated consists of a metal bar having some resiliency and having the ends 10 and 11 bent inwardly toward each other so as to provide a rail base embracing yoke, the body portion of which is designated by the reference character 12. The end portion 10 is formed with a relatively sharp bend, the extremity of which provides a jaw 13 which hooks over and bears against the inclined top surface 14 of the rail base 15. The said jaw 13 is preferably formed at such angles that the under surface 16 thereof will bear flat against the inclined surface of the rail base. This particular character of engagement may, of course, be varied to suit the desires of the user.

The extremity of the jaw 13 is preferably formed with a rounded cam surface 17 which bears against the upper longitudinal edge 18 of the rail base during the initial driving of the anchor toward its applied position, that is to say, toward the full line position shown in Fig. 3 of the drawing.

The end 11 of the resilient bar is somewhat longer than the jaw 13 and forms a spring arm 19, the inner surface 20 of which bears against the upper longitudinal corner 21 of

the rail base, both during the transverse applying movement of the anchor and when the anchor is in its applied position. The body portion 12 of the anchor is bent intermediate the said jaw and arm to provide a bearing surface 22 which bears against the bottom surface of the rail base at a point nearer to the jaw 13 than to the spring arm 19.

With the above arrangement of the end 10 bearings 16 and 20 with relation to the intermediate bearing 22, the movement of the anchor in a direction to force the jaw 13 upon the inclined top surface 14 of the rail base, tends to rock the body of the anchor about the 15 bearing surface 22 so as to force the inclined surface 20 of the spring arm 19 downwardly across the upper edge 21 of the rail base. It will be noted also that by reason of the fact that the bearing point of the arm 19 is a greater distance from the point of bearing 22 than the bearing point of the jaw 13, a differential leverage is exerted by the said jaw 13 and arm 19 at their points of bearing on the rail base, with respect to the intermediate bearing 22. As the anchor is driven further upon the rail, the angle formed by the portions A and B of the body and the angle formed by the portions B and C are both increased by the flexing of the bar so as to exert 25 spring pressure both vertically and transversely of the rail.

In applying the anchor to a rail, the spring arm 19 is first hooked over one flange of the rail base, as indicated in Fig. 2 of the drawing. The jaw end 10 is then raised and the body is shifted slightly toward the right until the cam surface 17 of the jaw 13 engages the upper longitudinal corner 18 of the rail base. This position of the anchor is indicated in 35 dotted lines in Fig. 3 of the drawing, in which position it will be noted that the bearing 22 is in engagement with the bottom face of the rail base. The anchor device is then driven bodily transversely of the rail by striking 40 the jaw end 13 of the anchor so as to force the jaw 13 upwardly on the inclined surface 14 of the rail base. This inward movement of the jaw 13, by reason of the differential arrangement of the jaw 13 and the spring arm 19, with relation to the bearing 22, tends 45 to rock the body of the anchor about the bearing 22 so as to move the spring arm 19 downwardly across the edge 21 of the rail base. The inner surface 20 of the arm 19 functions 50 as a cam during the said downward movement of the arm so as to flex the arm 19 outwardly with respect to the rail. This outward flexing of the arm, as before referred to, increases the angle formed by the portions B 55 and C of the yoke. The inward movement of the jaw 13 also flexes the body portion 12 so as to increase the angle formed by the portions A and B and, to some extent, distorts the jaw 13 with relation to the body. The 60 arm 19 is preferably so disposed that when 65

it is in its normal applied position it extends at substantially 45° with respect to the vertical edge 23 of the rail base. The tendency which the body portion 12 and the arm 19 have to return to the position from which they have been sprung, exerts spring pressure vertically and transversely of the rail so as to press the bearing surfaces 16 and 22 into firm gripping engagement with one flange of the rail base and to exert pressure transversely of the rail in a direction tending to force the jaw 13 inwardly on the rail base.

With the above arrangement and operation, the anchor device will automatically assume its normal gripping position after it has been subjected to some disturbing influence. If the end 11 of the anchor, by reason of it being embedded or pressed downwardly on the ballast of the road-bed, is forced upwardly with relation to the rail 85 base, in a manner to relieve the gripping pressure on the corner 21 of the rail base, the spring tension of the anchor, together with the inclined surface 20 of the arm, will, upon the removal of the disturbing influence, cause 90 the anchor device to be moved back into its normal gripping position and thereby prevent the jaw 13 from backing off the rail base.

The particular angle at which the arm 17 is formed with relation to the body portion 12 of the anchor, also simplifies the manufacture of the device in that the bend 11 may be formed with dies of such character as to prevent the body 12 or the arm 19 from springing away from the die, after the bending pressure has been relieved.

I claim:

1. A rail anchor consisting of a rail base embracing member provided with a bearing for engagement with the bottom surface of the rail base and provided with gripping portions for engaging the rail base at opposite sides of the rail; the said gripping portions being differentially disposed with relation to said bearing against the bottom and at different angles relative to the bottom surface of the rail, whereby movement of the rail embracing member transversely of the rail to its applied position so stresses the said member as to exert spring force lengthwise of said member tending to move the anchor in a direction to increase its grip on the rail.

2. A rail anchor consisting of a rail base embracing member provided with a bearing for engaging the bottom surface of the rail and provided with gripping portions for engaging the rail base at opposite sides of the rail; the said gripping portions being differentially disposed with relation to said bearing against the bottom and at different angles relative to the bottom surface of the rail, whereby movement of the said rail embracing member transversely of the rail to its applied position so stresses said member as to exert spring force both vertically of the rail and

longitudinally of said member in a direction tending to force the anchor into tighter engagement with the rail base.

3. A rail anchor comprising a body provided with a portion for bearing against the bottom surface of the rail base and with inwardly projecting portions which project over the upper surfaces of the rail base and grip the rail base at opposite sides of the rail, the said gripping portions being differentially disposed with relation to the point of bearing against the bottom surface of the rail and at different angles relative to the bottom surface of the rail base, whereby the movement of the body transversely of the base to its applied position thereon, so stresses the body and gripping portions thereof as to exert spring force both vertically of the rail base and lengthwise of the body in a direction tending to force the anchor into tighter engagement with the rail base.

4. A rail anchor comprising a body formed at one end with a jaw for bearing against the top surface of a rail base, at the other end with a spring arm disposed at an angle of substantially 45° relative to the vertical edge of the rail base and adapted to bear against the upper longitudinal corner only of the rail base at the other side of the rail, and formed intermediate said jaw and arm with a portion for bearing against the bottom surface of the rail base at a point nearer to said jaw than to said arm, whereby the movement of the body transversely of the rail in a direction to force said jaw inwardly on the top surface of the rail base rocks the anchor about said bottom bearing and forces said arm into spring gripping engagement with the said upper longitudinal corner of the rail base.

5. A rail anchor comprising a body formed at one end with a jaw for bearing against the top surface of a rail base, at the other end with a spring arm disposed at an angle to bear against the upper longitudinal corner only of the rail base at the opposite side of the rail, and formed intermediate said jaw and arm with a portion for bearing against the bottom surface of the rail base at a point nearer to said jaw than to said arm, whereby movement of the body transversely of the rail in a direction to force said jaw inwardly on the top surface of said rail base so distorts the body and said arm portion thereof as to exert spring force tending to move said jaw inwardly on the rail base and to hold said jaw and said bottom bearing in firm gripping engagement with the top and bottom surfaces respectively of the rail base.

6. A rail anchor adapted to be driven in the direction of its length from one side of a rail into gripping engagement with the rail base and comprising a bar formed at one end with a portion for gripping the top and bottom surfaces of the rail base at one side of the rail and at the other end with an inwardly pro-

jecting arm for bearing at the other side of the rail against a longitudinal corner only of the rail base, and exerts spring pressure transversely of the rail in a direction tending to increase the grip on the rail base.

70

7. A rail anchor adapted to be driven in the direction of its length from one side of a rail into gripping engagement with the rail base and comprising a bar formed at one end with a portion for gripping the top and bottom surfaces of a rail base at one side of the rail and at the other end with an inwardly projecting arm for bearing at the other side of the rail against the upper longitudinal corner only of the rail base and exerts spring pressure transversely of the rail in a direction tending to increase the grip on the rail base.

75

8. A rail anchor adapted to be driven in the direction of its length from one side of a rail into gripping engagement with the rail base and comprising a bar formed at one end with a jaw formed with a bearing surface for engaging the top surface of the rail base at a point remote from the longitudinal edge thereof and provided at its extremity with a cam surface, at the other end with an inwardly extending arm for bearing against the upper longitudinal corner only of the rail base at the other side of the rail, and provided intermediate said jaw and arm with a portion for bearing against the bottom of said rail; the said jaw and arm being differentially disposed with relation to said bottom bearing, whereby said arm is moved downwardly across said longitudinal corner of the rail base and flexed outwardly relative to said rail by the movement of said cam surface across said upper longitudinal corner of the rail base.

90

100

9. A rail anchor adapted to be driven in the direction of its length from one side of a rail into gripping engagement with the rail base and comprising a bar formed at one end with a jaw having a flat bearing surface for engagement with the top surface of the rail base and provided at its extremity with a cam portion, at the other end with an inwardly extending spring arm for bearing against the upper longitudinal corner only of the rail base, at the other side of the rail, and provided intermediate said jaw and arm with a portion for bearing against the bottom of the rail; the said jaw and arm being differentially disposed with relation to said bottom bearing, whereby the movement of the anchor transversely of the rail rocks the anchor about said bottom bearing to move said arm downwardly across the edge of the rail and flexes the body and arm to exert spring pressure, vertically of the rail and transversely of the rail in a direction tending to increase the said vertical pressure.

110

115

120

125

10. A rail anchor comprising a yoke member formed with jaws for engagement with opposite edges of a rail base and adapted to

130

be moved to their gripping positions by movement of the yoke transversely of the rail, one of said jaws being disposed to exert its grip vertically of the rail and the other of said 5 jaws being disposed to exert spring pressure transversely of the rail in a direction to increase said vertical grip.

11. A rail anchor comprising a yoke member formed with a portion for bearing 10 against the bottom surface of a rail base and with jaws for engagement with the opposite edges of the base and adapted to be moved to their gripping positions by movement of the yoke transversely of the rail, one of said jaws 15 being disposed at an angle to the other jaw and so positioned with respect to the portion for bearing against the bottom surface of the rail base that transverse movement of the yoke subjects it to a rocking movement about 20 an axis extending longitudinally of the rail and thereby positions said other jaw to exert spring pressure longitudinally of the yoke in a direction to increase the grip of the anchor on the rail.
12. A rail anchor comprising a yoke member formed with a portion for bearing against the bottom surface of a rail base and with jaws for engagement with opposite edges of the base and adapted to be moved to their 25 gripping positions by movement of the yoke transversely of the rail, one of said jaws being disposed at an angle to the other jaw and so positioned with respect to the portions for bearing against the bottom surface of the rail 30 that said transverse movement of the yoke subjects it to a rocking movement about an axis extending longitudinally of the rail and thereby positions said other jaw to exert spring pressure both vertically and longitudinally of the yoke.

13. A rail anchor comprising a yoke

formed with a portion for bearing against the bottom of a rail base and with jaws for gripping the top portion of the base flange; one of said jaws being disposed at an angle of substantially 45° relative to the vertical edge of the rail base and adapted to engage a longitudinal corner of said base to exert spring pressure transversely of the rail.

14. A rail anchor comprising a yoke formed 50 with a portion for bearing against the bottom surface of a rail base and with jaws disposed at different distances from the bottom bearing portion and at an angle to each other, whereby movement of the anchor transversely 55 of the rail base rocks one of said jaws downwardly into gripping engagement with the rail base; said last mentioned jaw being confined in its engagement with the said base to the upper longitudinal corner thereof and 60 adapted to exert spring pressure transversely of the rail tending to increase the grip of the outer jaw on the rail.

15. A rail anchor comprising a yoke formed 65 with a portion for bearing against the bottom of a rail base and with jaws disposed at different distances from the bottom bearing portion and at an angle to each other, whereby movement of the anchor transversely of the rail rocks one of said jaws downwardly into 70 gripping engagement with the rail base; said last mentioned jaw being disposed at an angle to the top surface of the rail base and is confined in its engagement with said base to the upper longitudinal corner thereof, whereby 75 the downward movement of the said jaw flexes it outwardly and upwardly relative to the said longitudinal corner of the rail base so as to prevent movement of the anchor in a direction to loosen its grip.

JOHN A. EVANS.

CERTIFICATE OF CORRECTION.

Patent No. 1,682,218.

Granted August 28, 1928, to

JOHN A. EVANS.

It is hereby certified that error appears in the printed specification of the above numbered patent requiring correction as follows: Page 3, line 1, claim 2, after the word "member" strike out the words "in a direction tending to force the anchor into tighter engagement with the rail base" and insert instead "tending to move the anchor in a direction to increase its grip on the rail"; and that the said Letters Patent should be read with this correction therein that the same may conform to the record of the case in the Patent Office.

Signed and sealed this 2nd day of October, A. D. 1928.
